UNITED STATES PATENT OFFICE

2,570,344

TRACKWAY GUIDED BED

Walter L. Hoffmann, Flushing, and Arthur E. Lennstrom, Richmond Hill, N. Y.

Application March 8, 1950, Serial No. 148,392

5 Claims. (Cl. 5—145)

1

The invention relates to trackways for use with furniture, for example, beds.

The storing of a bed in a minimum of space is greatly to be desired by residents of apartments, hotels, dwellings and other places where every foot of floor area is valuable.

Heretofore beds have been utilized which fold upwardly in their entirety into recessed wall cabinets provided for the purpose, for example, the "Murphy bed"—but these require valuable space which might otherwise be used for closets or the like.

A principal object of the invention comprehends the provision of means for employment with a bed, or other articles of furniture, which will accomplish the storing thereof in a relatively shallow space or cabinet, when the bed is not in use—thus rendering the maximum floor area available.

Another object includes structure which can be manipulated with facility and is devoid of intricate parts which may require mechanical adjustment or repair.

Another principal object contemplates trackways which may be utilized to entirely withdraw a bed or other article of furniture from the confines of a cabinet or the like.

These and other objects will be apparent as a description of the invention, taken together with the drawings, unfolds.

Briefly described, the invention includes a pair of standards or uprights, upon which are pivotally and eccentrically supported a pair of trackways adapted to slidably receive the lower extremities of two legs of a bed. The standards or uprights may, if desired, be mounted in a cabinet, on the floor, or in a recess provided therefor.

In the drawings:

Fig. 1 is a perspective view illustrating a bed collapsed and in upright position with the trackways in juxtaposition to or folded against the underside of the bed.

Fig. 2 depicts a perspective view showing the trackways in down position with two legs of a bed at the inner limits of the trackways, with a section of a cabinet shown.

Fig. 3 is a view showing a bed extended and erected at the outer limits of the trackways.

Fig. 4 shows a bed removed from the trackways.

Fig. 5 illustrates an alternative or modified trackway.

Fig. 6 is a side elevation of another modification of a trackway.

Fig. 7 is a plan view of the same modification.

2

Fig. 8 is a side elevational view of Fig. 6 showing the outer portion of the trackway in raised position.

The detailed description of the invention follows, and like numerals refer to like parts.

In the drawings, the uprights or standards 5 pivotally and eccentrically support in their recessed, upwardly extending, spaced apart, extensions 6—a pair of channeled, parallel trackways 7. These latter members, in one form of the invention, have elongated, main portions 8, which may have outer ends 9 and toward the other or opposite ends 10 are bent downwardly or depressed to a slight degree, as at 11. The inner ends or portions 10 of the trackway in one embodiment assume a goose-neck or hook-like configuration, or in another form may be L-shaped, as depicted in the trackway 12 of Fig. 5 by the numeral 12a, with outer ends curved as in 12b.

20 In either form, the spaced apart extensions 6 accommodate and permit the ends 10, or 12a, to be received therebetween as the trackways are up-ended, as herein described.

Other configurations might be employed at the inner ends of the trackways which would permit the legs of a side of a bed to be supported thereby, when the trackways are up-ended. They may be relatively straight throughout, for example.

25 Trackways 7 have continuous side walls 13 and bottom 13a for slidably receiving and guiding the lower ends of bed legs and spaced inwardly from the inner ends we provide pintles 14 fixed therebeneath and extending oppositely from the bottom. Members 7, as stated before, are eccentrically and pivotally supported by standards or uprights 5 with the pintles 14 received in the recessed upper portions 6.

30 As shown, the two legs L of a bed B are slidably receivable in the trackways 7 and when moved to the outer limits of the trackways the bed may be extended for use, entirely removed from the confines of and proximity to the cabinet C. When it is desired to utilize the floor space occupied by the bed, it may be collapsed and propelled

35 inwardly toward the opposite ends of the trackways, as shown in Fig. 2. As the legs L move past the pivot point defined by the pintles 14 and the opposite end of the bed is moved in an upward and inward direction the inner ends of the trackways are depressed by gravity thus lifting the outer portions of the trackways to enfold and press against the underside of bed B with the ends 10 turned between extensions 6. The

40 45 50 55 upward slight bend in members 7 toward the inner ends

Fig. 7 is a plan view of the same modification.

is designed to assist in the manipulation of the bed as when it moves past the bend point any tendency of the bed legs to roll outwardly is precluded.

In practice, one preferred form of the invention utilizes a cabinet C wherein the standards or uprights 5 are secured to the bottom of the inside thereof and bed B when not extended for use may be expeditiously stored within the confines of the cabinet which may be provided with doors, making up a decorative and extremely useful piece of furniture. As an alternative, a skeleton structure of the size of the frame of cabinet C might be employed, or the uprights 5 conceivably could be mounted on the floor next to a wall, or in a wall recess. We do not desire to limit the positioning or location of the uprights.

It is contemplated that beds other than collapsible might be employed, even couches, and furthermore, as shown in Fig. 4 we comprehend that the side legs of bed B may be removed, with the utmost facility, from the limits of trackways 7 and the bed moved to whatever position in the room that is deemed most desirable.

Additionally, it is proposed that any material having the necessary strength and rigidity may be used in manufacturing our invention.

In the modification depicted in Figs. 6, 7, 8, the trackway indicated by the numeral 15 is hinged at 16, is provided at the hinge region with an angular cut-out 17 in the side walls 18. The inner ends of the trackways 15 are raised as at 19, and the limits of said ends are recessed or depressed at 20. The rollers R, indicated in dotted lines, having pins P are slideable in this trackway and the rollers R supported on pins P as they travel over the raised portions 19 are precluded from accidental dislodgement. As depicted in Fig. 8 the outer portions of the modified trackway can be elevated to upright position, when desired. Additionally, any tendency of rollers R to roll outwardly is prevented by recessed or depressed portions 20.

In all embodiments of the invention disclosed, the inner terminal portions of the trackways carry or sustain the weight of the bed or other article when the outer portions of the trackways are elevated.

We reserve the right to make such changes or modifications as may come within the scope of the appended claims.

We claim:

1. The combination of a channeled member and a standard supporting said member, said member having a bottom and a pair of oppositely disposed side walls extending in the same direction from said bottom and cooperating therewith to form a trackway adapted to guidably receive a part projecting from a structure to be carried by said member, a pintle carried by and extending in opposite directions from the member, said member comprising an elongated portion and a shorter portion, said portions ex-

tending in opposite directions from the location of said pintle, the standard comprising a base and a pair of parallel elements extending in the same direction from said base and pivotally receiving said pintle, said shorter portion being hook-shaped and having a curved bight portion forming a pocket between said pintle and the outer end of said shorter portion for receiving the part projecting from said structure and cooperating with the projecting part to swing said channeled member about said pintle.

5 2. The structure as defined in claim 1 wherein the pocket is depressed with respect to the rest of the channeled member and the pintle is pivotally and removably received by the parallel elements.

10 3. The structure as defined in claim 1 wherein the pintle is carried by the bottom of the channeled member.

15 4. The combination of a bed including a pair of legs pivoted beneath one end thereof and another pair of legs pivoted beneath the other end, a pair of channeled members each having a bottom and a pair of oppositely disposed side walls extending in the same direction from said bottom and cooperating therewith to form a trackway, each trackway slidably receiving the free end of one of said legs, the channeled members extending in parallelism to each other, a pintle carried by and extending in opposite directions from each of said channeled members, each channeled member comprising an elongated portion and a shorter portion, the portions extending in opposite directions from the locations of the pintles, a pair of standards each comprising a base and including a pair of parallel elements extending in the same direction from said base and pivotally receiving the pintles, each shorter portion being hook-shaped and having a curved bight portion forming a pocket between said pintle and the outer end of said shorter portion for receiving the end slideable in the channeled member and for cooperating with said end to swing the channeled member about its pintle.

20 5. The structure as defined in claim 4 in which each of the pockets is depressed with respect to the rest of its channeled member and the pintles are carried by the bottom of the channeled members and are pivotally and removably received by the pairs of parallel elements.

25 WALTER L. HOFFMANN.
